UNITED STATES PATENT OFFICE

ROSCOE E. MAJOR, OF CHICAGO, ILLINOIS, ASSIGNOR TO MAJOR EQUIPMENT CO., INC., A CORPORATION OF ILLINOIS

LAMP SOCKET

Application filed April 30, 1930. Serial No. 448,708.

The main object of this invention is to provide an improved form of lamp receptacle which can be installed in an aperture on a plate or in a conduit outlet box, and is provided with improved means for securing it in place and for holding a lamp reflector.

An illustrative embodiment of this invention is shown in the accompanying drawings in which:

10 Figure 1 is a front view of a lamp receptacle, designed for mounting on one side of a plate for attaching a lamp and reflector on the other side.

Fig. 2 is a back view of the same.

15 Fig. 3 is a cross section on the line 3—3 of Fig. 1.

Fig. 4 is a fragmentary view of the front plate of a conduit box with the receptacle in place in one of the apertures.

20 Fig. 5 is a fragmentary sectional view of a reflector adapted for use with such receptacles.

Fig. 6 is a sectional view on the line 6—6 of Fig. 5.

25 Fig. 7 shows the face of a conduit box with a receptacle installed, and the base of the reflector locked in place.

Fig. 8 is a section taken on line 8—8 of Fig. 7.

30 In the form shown in the drawings the lamp receptacle body 1 may be formed of molded insulating material, such as thermophase. The receptacle body 1 is provided with four symmetrically placed wing or

35 pilaster projections 2. Centered in each pilaster projection is a molded-in metal insert 3, which is internally threaded to receive a round-head machine screw 4. Centrally located in the lamp receptacle body

40 1 is a well 5, which forms the housing for a screw shell 6, which is provided with base flanges 7. On top of the flanges 7 are placed washer plates 8, and screws 9, which mechanically fasten the screw shell 6 to the

45 terminal yoke 10. The center lamp terminal is installed in the bottom of the well, and comprises a slidable metal plunger 11, which is normally held in a fixed position by a bent lever spring 12, and also by a helical spring 13, which is seated on a ledge

in the plunger aperture. The lever spring 12 is mechanically secured to the center lamp terminal 14 by screw 15.

The assembly comprises bending a straight lever spring at right angles, placing the screw 15 in locking position, bending the lever spring to its normal position, inserting the coil spring 13, and then placing the metal plunger 11, which is of tubular rivet form at the lower end. The tubular rivet end is upset over the center terminal 14. The line wire securing screw 16 engages threads in the center terminal 14. The terminal yoke 10 has a similar line wire terminal screw 17, which engages a metal insert 18, molded in the lamp receptacle body. The face plate 19 is provided with apertures 20, comprising a circular cutout 21, and a symmetrical overlying rectangular cutout 22, the rectangular cutout having a length substantially twice the diameter of the circular portion and a width about one-third of such diameter.

Located at right angles to the longitudinal axis of the rectangular cutout are punched perforations 23, which are placed to receive the screws 4, which are threaded into the metal inserts 3 of the receptacle. The receptacle face has four machine screws 4, two of which are used to fasten the receptacle to the plate 19, and the other two are exposed through the rectangular cutout.

The base of the lamp reflector has a central outlet 24, and four perforations 25, each large enough to pass the heads of the screws 4. Two of the apertures are offset circumferentially from symmetrical position, and the offset apertures are provided with key hole bayonet slots 26, which pass the shank of the screw 4.

The installation of this improved socket with its reflector consists in placing the socket in the outlet aperture of the plate and securing the socket to the plate by two screws, the heads of which project above the plate. The two screws left exposed are then loosened, and the offset keyhole perforations in the reflector base are passed over the heads of the screws. The reflector body

is then turned to the right and the bayonet slots engage the two loosened screws. When the reflector body is so turned, the two round apertures without slots will register over the screw heads which secure the receptacle to the plate. When the loosened screws are tightened, they mechanically hold the reflector to the conduit box, and the projecting screw heads act as stops and prevent the rotation of the reflector body.

From the construction, the riveted center lamp terminal is not removable. The screw shell is removable without disturbing the relative position of the parts or the wiring, since the line wire terminal screw on the yoke is threaded into the body of the receptacle. Hence, the screw shell can be removed without changing the position of the yoke. In a similar manner the lamp reflector can be removed and replaced by backing out the two screws which perform no other function other than that of holding the lamp reflector.

Although but one specific embodiment of this invention is herein shown and described, it will be understood that details of the construction shown may be altered or omitted without departing from the spirit of this invention as defined by the following claims:

I claim:

1. An electrical outlet comprising a lamp receptacle, a base plate having an outlet aperture, and having large and small perforations arranged about said aperture, a reflector having an outlet aperture and having round and key hole perforations arranged about said aperture, a pair of plate attaching screws in said receptacle coacting with the small perforations in said base plate, and a pair of reflector attaching screws coacting with the key hole perforations in said reflector, and said round reflector perforations registering with the heads of the plate attaching screws.

2. An electrical outlet comprising a lamp receptacle, symmetrically placed screws threaded into the body of said receptacle, a base plate having an outlet aperture, symmetrically placed perforations in said plate, some of said perforations being smaller than the heads of said screws, others larger than the heads of said screws, a lamp reflector having round and key hole perforations about the outlet aperture registering with the perforations in said plate, said receptacle being fastened to said base plate by screws through the small perforations with the heads projecting above the base plate, said reflector being fastened to said receptacle by screws through the key hole perforations in said reflector and the larger perforations in said plate, and the heads of the plate fastening screws coacting with the round perforations in said reflector.

3. An electrical outlet comprising a base plate having an outlet aperture and having a plurality of perforations arranged about said aperture, a lamp receptacle, headed screws threaded into said lamp receptacle, certain of said perforations being larger than the heads of said screws, and certain perforations being smaller than the heads of said screws, a reflector having round and keyhole perforations registering with said plate perforations, said receptacle fastened to said plate by screws in the smaller perforations in said plate, said reflector fastened to said receptacle and plate by screws using the keyhole perforations in said reflector, the heads of the receptacle fastening screws registering with round perforations in said reflector requiring backing out of said reflector fastening screws to release said reflector from coaction with said receptacle fastening screws.

4. A lighting fixture comprising a supporting plate having a socket aperture, a receptacle body having a projecting rim fitting said aperture, a lamp housing having a base apertured to fit said receptacle rim, a pair of oppositely located headed screws threaded into said receptacle body for fixing said receptacle on said plate, a second pair of oppositely located headed screws threaded in said body, said plate being apertured for said screws, and said housing having in its base a pair of apertures to receive the heads of said first named pair of screws and a pair of key hole slots positioned and shaped to receive the second pair of said screws when said first pair of apertures are out of alignment with their respective screws and to permit rotation of said housing on the second pair of screws to bring said apertures into engagement with the heads of said first pair of screws.

Signed at Chicago this 26 day of April 1930.
